[57] **CLAIM**

The ornamental design for a pot with hinged lid, as shown and described.

DESCRIPTION

FIG. 1 is a front elevational view of a pot with hinged lid showing my new design;

FIG. 2 is a side elevational view thereof from the left of FIG. 1, with the lid partially raised, the side opposite that shown in FIG. 2 being the mirror image thereof;

FIG. 3 is a rear elevational view thereof;

FIG. 4 is a top plan view thereof;

FIG. 5 is a bottom plan view thereof; and,

FIG. 6 is a cross-sectional view thereof on the line 6—6 of FIG. 4.
